UNITED STATES PATENT OFFICE

1,935,760

CLOCK

Clarence E. Amburgey, Norton, Va.

Application July 21, 1932. Serial No. 623,874

4 Claims. (Cl. 58—46)

This invention relates broadly to clocks, and has more particular reference to means whereby wind power may be utilized to wind up the clock.

- In accordance with the present invention, there is provided what may be termed a "self winding clock", in that the invention consists in the provision of a power transmission mechanism connected to the clock for utilizing wind power to wind up the spring motor of the clock.
- 10 The invention together with its numerous objects and advantages will be best understood from a study of the following description, taken in connection with the accompanying drawings wherein:

15 Figure 1 is a front elevational view of the device.

Figure 2 is a top plan view thereof.

Figure 3 is a fragmentary rear elevational view thereof, with the rear cover plate of the 20 sign board removed,

Figure 4 is a transverse sectional elevational view,

Figure 5 is a fragmentary sectional elevational view through a portion of the spring motor, and

25 Figure 6 is a plan view of a combined gear wheel and ratchet forming part of the invention.

Referring more in detail to the drawings it will be seen that invention comprehends the provision of a base having a standard 6 rising therefrom, 30 and rotatably mounted on the standard is what may be termed the sign board designated generally by the reference character 7.

The sign board comprises upper and lower frame members 8, 9, end frame members 10, and 35 front and rear plates 11, 12 suitably secured to the frame members 8, 9 and 10.

The upper portion of the standard 6 extends through a bushing 13 provided in the bottom frame member 9, and on its upper end the standard 6 is provided with a bearing part 14. Connecting intermediate portions of the frame bars 8 and 9 are relatively spaced bars 15 which in turn are connected by a cross bar 16. The cross bar 16 has suitably mounted therein a bearing part 14a coacting with the coacting part 14 as 45 shown in Figure 3. Thus it will be seen that the signboard 7 is mounted for rotation on the standard 6.

Supported between the upper ends of the bars 50 15 is a plate 17 on which is suitably mounted a clock 18, and in this connection it will be seen that the front sign board plate 11 is provided with an aperture 11a for accommodating the front or face portion of the clock. For driving 55 the clock 18 there is provided a conventional

spring motor designated generally by the reference character 19, and the same includes a shaft 20 about which the spring motor is properly disposed, and said motor as shown in Figure 5 is provided with a hub or sleeve 21 mounted on the shaft 20 for rotation relative thereto. A gear 22 is slidably mounted and on one end of the shaft 20 and the hub of the gear 22 has a ratchet face 23 cooperating with a similar ratchet clutch on one end of the sleeve or hub 21 for transmitting power from the gear 22 to the hub. A spring 24 is arranged on one end of the shaft 20 and one end of the spring bears against the gear 22, while the other end of the spring bears against a head 20a provided on said shaft 20; spring 24 thus serving to normally retain the gear 22 and clutch to the hub or sleeve 21.

For driving the gear 22 there is provided a suitable reduction gearing designated generally by the reference character 25 and mounted on the plate 17. The transmission gearing 25 includes also a relatively small pinion gear 25a mounted on a shaft suitably journaled in a bracket 26 fixed to the plate 17.

Connected with the shaft on which the pinion gear 25 is secured, is a spring 27 which has an end thereof secured in a plug 28 fixedly arranged in the upper end of the standard 6.

From the above it will be apparent, that as the signboard 7 rotates about the longitudinal axis of the standard 6, the end of the spring 27 is anchored to the standard 6, a rotation of the shaft on the pinion gear 25 will be effective and drive transmitted therefrom through the reduction gearing to the hub 24 resulting in a so winding of the spring motor. Thus it will be seen that I have provided a device which will be found especially useful as an advertising clock for jewelers, and one which will not require a great deal of attention, and yet at the same time will be maintained in a suitably wound condition.

It will be noted, either or both plates 12 may be utilized for supporting signs or other advertising data as suggested in Figure 1 and there is preferably also provided at each end of the signboard a wind vane 29, the wind vane 29 extending in an opposite direction as indicated in Figure 2.

Even though I have herein shown and described the preferred embodiment of the invention, it is to be understood that the same is susceptible of further changes, modifications and improvements coming within the scope of the appended claims.

Having thus described my invention, what I claim as new is:

1. In a device of the character described, a standard, a support mounted on the standard for rotation relative thereto, a clock carried by said support, and power transmission means connected with the clock and with said standard for utilizing rotative movement of the support to wind the clock.
- 10 2. In combination, a standard, a support rotatably mounted on said standard, a clock carried by said support, a spring motor for said clock, a shaft mounted on said support and having its axis disposed at right angles to the axis of said standard, transmission gearing connecting said shaft with said spring motor, and a spring secured at one end to said shaft, and at its other end to said standard.

20

80

3. A device for utilizing wind power for winding clocks comprising a rotatable member, a fixed member about which the first named member is rotatable, a clock carried by the rotatable member and including a motor, and power transmission means connecting the motor of said clock with said fixed member.

4. A device for utilizing wind power comprising a supporting structure, a member rotatably mounted on said supporting structure, a spring motor carried by said rotatable member, and including a shaft, a hub on said shaft, and a spring having an end anchored to said hub, a gear on said shaft, hub means connecting said gear with the hub, and driving means for said gear including a spring having an end anchored to the supporting structure.

CLARENCE E. AMBURGEY.
